CLAIM

The ornamental design for a storage box, as shown and described.

DESCRIPTION

FIG. 1 is a top front perspective view of a storage box showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof;

FIG. 7 is a top rear perspective view thereof;

FIG. 8 is a bottom rear perspective view thereof;

FIG. 9 is a top rear perspective view, showing two fasteners of the storage box in an open configuration; and,

FIG. 10 is a bottom rear perspective view, showing two fasteners of the storage box in an open configuration.

The dashed broken lines in the figures show portions of the storage box that form no part of the claimed design.

1 Claim, 10 Drawing Sheets
